DESULFURIZATION OF DISTILLATE FUELS

Robert C. Arnold, Chicago Heights, Ill., assignor
to Standard Oil Company, Chicago, Ill., a cor-
poration of Indiana

Application June 23, 1950, Serial No. 169,914

7 Claims. (Cl. 196—14.47)

1

This invention relates to the treatment of straight-run petroleum oils for the purpose of reducing the sulfur content. More particularly the invention is directed to the treatment of heavy naphtha, i. e., a material boiling between 250—425° F., kerosene, diesel oil, furnace oil and heater oil, i. e., a material boiling between 325 and 575° F., which oils contain organic sulfur compounds in amounts, on a total sulfur basis, varying from about 0.3 to about 1.5 weight percent. Collectively these straight-run petroleum oils are referred to herein as distillate fuels.

The presence of sulfur in hydrocarbon oils that are to be used in gasoline and diesel engines and in domestic type heating units is believed to be undesirable even though not proved as harmful. It is thought that gasoline should be less than 0.15 weight percent sulfur content and preferably less than 0.10% sulfur. Although the basis for the limitation is somewhat vague at this time, it is thought that fuels for domestic type heating units, both space heaters and furnaces, should contain less than about 0.4% and preferably less than 0.3% sulfur. Excessive amounts of aromatic hydrocarbons are undesirable in such fuels because of carbon depositing tendencies; those aromatics removable with small amounts of liquid sulfur dioxide appear to be particularly harmful in this respect.

It is known to treat sulfur and aromatic bearing distillates with sulfuric acid but this process has the serious drawback of degrading large amounts of oil into virtually valueless sludge. In some cases uneconomically large amounts of acid must be used to reduce the sulfur content to a satisfactory point. The dearomatization of kerosene with liquid sulfur dioxide also results in a lowering of the sulfur content of the raffinate oil, but does not remove a sufficient amount of sulfur compounds, with a reasonable treating loss, to meet strict specifications.

An object of this invention is to produce petroleum distillate fuel of sulfur content suitable for use in domestic type heating units and automotive engines and to produce an oil low in sulfur and low in objectionable aromatic constituents for use in distillate fuels. A specific object of this invention is to provide a process for making satisfactory distillate fuels from straight run petroleum distillates containing objectionable amounts of organic sulfur compounds and aromatics by treating these distillates with liquid sulfur dioxide and sulfur trioxide in such proportions and under such conditions that maximum yields of usable oils are obtained and by-products

2

are in the form of a high sulfur extract instead of a sludge.

I accomplish the above objects by treating a virgin high sulfur distillate fuel at a temperature between 20° C. and —40° C., e. g., —10° C. with an amount of liquid SO₃ in the range of about 1% to 5% by volume (based on distillate) and with an amount of liquid SO₂ in the range of about 10% to 80% by volume (based on distillate) for a time of contact in the range of about one to sixty minutes followed by separation of resulting phases and removal of SO₂ from each phase, the raffinate phase preferably being caustic washed after SO₂ removal. For optimum results the amount of SO₂ should be in the range of 50—80% when SO₃ is 1%, 20—60% when SO₃ is 2%, 15—50% when SO₃ is 3% and 10—40% when SO₃ is 4%. Unlike the process of U. S. 1,791,941, my process is directed to desulfurization, the conditions are such as to produce an extract as a by-product instead of a sludge, and the relative proportions of SO₂ and SO₃ are in that critical range which is required for obtaining an amount of desulfurization which is disproportionate to treating loss.

As illustrations of the results obtainable by treating a high sulfur virgin heater oil (obtained from West Texas crude) with liquid SO₂ and sulfur trioxide,

Figure 2 shows the amount of extract material removed by treatment with liquid SO₂ solvent alone and with liquid SO₂ plus certain amounts of sulfur trioxide.

Figure 1 shows the desulfurization obtained, as percent of the original sulfur content, by treatment with liquid SO₂ solvent alone and with liquid SO₂ plus the amounts of sulfur trioxide listed in Figure 2.

The data for the figures were obtained by treating a West Texas virgin heater oil having the following inspections:

°API	40.2
Sulfur (lamp)	weight percent 0.73
ASTM Distillation:	
IBP	°F 332
10%	°F 390
50%	°F 446
90%	°F 502
Max.	°F 548

(The sulfur content of virgin heater oils from high sulfur crude normally runs between 0.6 and 1.0 weight percent.) About 200 ml. of raw distillate were placed in a separatory funnel and chilled to —20° C. in a Dry Ice-acetone bath.

3

The indicated amount of sulfur trioxide was dissolved in the indicated amount of liquid SO_2 and the solution was added to the raw oil in the separatory funnel. The funnel was shaken to obtain equilibrium and allowed to settle when the SO_2 layer containing aromatic and sulfur compounds was separated. The total contact time was on the order of 2-3 minutes. Shorter contact times may be used successfully but contact times up to 2 hours have been used; these long contact times tend to promote undesirable color in the raffinate oil. The separated raffinate was stripped to remove SO_2 and was washed with caustic solution and water. For example, when 28 volume percent of liquid SO_2 and 2 volume percent of liquid sulfur trioxide were added to 200 ml. of the high sulfur virgin heater oil distillate, a raffinate yield of 91% was obtained having a sulfur content of 0.24 weight percent, corresponding to a 63% desulfurization. Using 28 volume percent of liquid SO_2 alone, the desulfurization obtained was only 28% with a raffinate yield of 96%.

West Texas virgin heavy naphtha with 0.32 weight percent sulfur was treated, at the same conditions as for the heater oil experiments, with 96 volume percent of liquid SO_2 and 4 volume percent of sulfur trioxide to produce a 76% yield of raffinate having 0.05% sulfur whereas 100 volumes of liquid SO_2 alone produced a 79% yield of raffinate having a 0.16% sulfur.

Figures 1 and 2 show that the addition of sulfur trioxide to the liquid SO_2 results in a remarkable and unpredictable improvement in desulfurization efficiency of the solvent, with a relatively small increase in extract oil loss. Thus at 30 volume percent of SO_2 treatment, 6% of the distillate is lost to extract with only 29% desulfurization; when 3 volume percent of SO_3 is added to the 30 volume percent of SO_2 , 11% of the distillate is lost to extract and 80% of the sulfur is removed. This 180% improvement in desulfurization with only 85% increase in extract loss is very surprising.

The results on treating distillate containing 0.73% sulfur indicate that about 4 volume percent of SO_3 is the maximum amount that can be used beneficially. The difference in desulfurization between 4 and 5 percent is very slight, in fact almost within the error of the determination; however, the loss to extract did increase even though little further desulfurization occurred. The data show that no worthwhile improvement in desulfurization takes place as the amount of SO_2 approaches close to 80 volume percent when 1% of sulfur trioxide is being used. The point of maximum effectiveness of each increment of SO_2 decreases as the amount of sulfur trioxide used increases. At 2 volume percent of sulfur trioxide, no worthwhile improvement is obtained by using more than about 60 volume percent of SO_2 ; the maximum desirable amount of SO_2 at 3 and 4% of sulfur trioxide usage are about 50% and 40%, respectively.

For a distillate fuel having a sulfur content much higher than the 0.7% example used herein, the maximum amount of sulfur trioxide needed may be more than 4% but not more than 6% even with a 1.5% sulfur content raw oil.

In order to obtain a heater oil of satisfactory sulfur content, i. e., about 0.3%, about a 60% desulfurization is needed when the raw distillate contains about 0.8% sulfur. This degree of desulfurization is not attainable with liquid SO_2 75 and 2 volume percent of sulfur trioxide.

4

alone without excessive losses of oil to extract and large treats of solvent. Figure 1 shows that this desulfurization can be obtained at 2% sulfur trioxide usage with about 20% of liquid SO_2 usage; at 3% sulfur trioxide usage with about 15% of liquid SO_2 usage; and at 4% sulfur trioxide with about 10% of liquid SO_2 usage. At a temperature of -20°C , the miscibility of SO_2 in heater oil distillate is about 10% by volume, so that at least enough liquid SO_2 must be used to obtain a raffinate and an extract phase.

While it is possible to obtain substantially complete desulfurization by this process, the added amounts of both SO_2 and sulfur trioxide necessary to achieve this result make such a low sulfur content distillate fuel uneconomic for its normal use. A commercial installation must balance the cost of sulfur trioxide and the cost of handling the SO_2 in arriving at the preferred operating conditions. When a distillate of 0.6-1.0% sulfur is the type of feed stock, my preferred operating conditions are 2-3 volume percent of sulfur trioxide and liquid SO_2 ranging between the amount necessary to obtain phase separation, i. e., on the order of 10 volume percent, and about 60 volume percent; the exact conditions will depend on the amount of desulfurization desired.

It is indicated that the amount of desulfurization is dependent on both the amount of sulfur trioxide and the liquid SO_2 and the character of the desulfurization curves indicate that probably this phenomenon is more related to both extraction and chemical reaction than either alone. It is possible that the sulfur trioxide reacts with the sulfur compounds not extractable by the particular amount of SO_2 employed to form materials that assist the solution of the sulfur compounds in the liquid SO_2 . The formation of sulfonic compounds does not completely explain the phenomenon because experiments using liquid SO_2 and alkane sulfonic acids, specifically, methane sulfonic acid did not show any marked improvement over SO_2 alone. For example, under conditions as given above, high sulfur distillate was treated with 48 volume percent of liquid SO_2 and 3.3 volume percent of methane sulfonic acid—46% desulfurization was obtained with 7% extract loss. A treat of 48% of liquid SO_2 alone resulted in 41% desulfurization at an extract loss of 8%.

The extract obtained from my process does not resemble in any way the sludge that is obtained by sulfuric acid treatment of an oil. The freshly separated extracts are tan-colored, mobile liquids which darken somewhat on standing. The extract from a run—18% liquid SO_2 and 2% sulfur trioxide—was quenched in ice water, caustic neutralized and steam distilled. The major portion of the extract came over as a light yellow liquid which contained 6% sulfur, had an API gravity of 20°; the color of this distilled extract did not change appreciably during storage.

My invention is applicable to distillate fuels obtained by distillation of crude or non-cracked oils, i. e., virgin or straight-run distillates. Tests on high sulfur catalytically cracked gas oils indicate that a satisfactory product can be obtained only at the cost of a large loss to extract. For example, a 29° API cycle stock from fluid catalytic cracking gave a 24% extract loss when treated with 28 volume percent of liquid SO_2 75 and 2 volume percent of sulfur trioxide.

In general my invention can be carried out in the conventional Edeleanu process equipment. While the preferred temperature of treatment is about -20° C., lower temperature or higher temperatures, up to ordinary room temperatures, can be used; but in all cases pressure sufficient to maintain the SO_2 in the liquid state must be used. Temperature below about 20° C. are preferable in order to prevent undesirable side reactions between the oil and the sulfur trioxide and maintain the selectivity of the SO_2 .

I claim:

1. A process of refining a high sulfur virgin petroleum distillate boiling between about 325° and about 575° F., which process comprises contacting said distillate at a temperature between about $+20^{\circ}$ and about -40° C. with an amount of liquid SO_2 from at least enough to form a separate extract phase to not more than about 40 volume percent, based on said distillate, and between about 1 and 5 volume percent of sulfur trioxide, based on said distillate, separating a raffinate phase from an extract phase, and recovering from said raffinate phase a product oil characterized by a sulfur content markedly lower than that of said distillate. 25
2. The process of claim 1 wherein said distillate has a sulfur content of between about 0.3 and about 1.5 weight percent. 15
3. The process of claim 1 wherein said distillate is a heater oil. 30

4. The process of claim 1 wherein said distillate is a kerosene.
5. The process of claim 1 wherein said distillate is a diesel oil.
6. The process of refining a virgin petroleum distillate boiling between about 325° and about 575° F. and containing between about 0.3 and about 1.5 weight percent sulfur, which process comprises contacting said distillate with a pre-formed mixture consisting essentially of liquid SO_2 , in an amount between about 20 and not more than about 40 volume per cent based on said distillate, and sulfur trioxide in an amount between about 2 and about 4 volume percent based on said distillate, at a temperature of about -20° C. for a time of between about 2 minutes and about 2 hours, separating a raffinate phase from an extract phase and recovering from said raffinate phase a product oil having a sulfur content markedly lower than that of said distillate.

7. The process of claim 6 wherein said distillate is a heater oil having a sulfur content of between about 0.6 and about 1.0 weight percent.

ROBERT C. ARNOLD.
